UNDERGROUND FLOW CONTROL VALVE ACCESS
HOUSING AND COMBINED COVER AND BASE
THEREFOR

John H. Thornton, Sr., Sheboygan, Wis., assignor to
Ametek, Inc., Sheboygan, Wis.

Filed Apr. 1, 1971, Ser. No. 130,184

Term of patent 14 years

Int. Cl. D25—99

U.S. Cl. D13—1 R

Fig. 1

Fig. 2

Fig. 3

FIG. 1 is a front perspective view of an underground flow control valve access housing and showing the combined cover and base member separated therefrom;

FIG. 2 is a generally similar view and showing the said member applied to the housing as a cover; and

FIG. 3 is a generally similar view and showing the said member applied to the housing as a base.

The rear of the housing is a mirror image of the front.

I claim:

The ornamental design for an underground flow control valve access housing and combined cover and base therefor, substantially as shown and described.
